METHOD AND DEVICE FOR SURVEYING
WELLSHarry P. Wickersham, Huntington Park, and
Gilbert V. Roberts, Maywood, Calif.

Application May 20, 1930. Serial No. 454,021

18 Claims. (Cl. 255—1)

This invention relates to a method and device for use in well drilling operations and relates more particularly to a method and a device for indicating and determining the deviation or inclination of a well bore from the vertical.

Deep wells, such as oil wells, are often drilled crooked. It is desirable for numerous reasons that a well bore be straight and therefore various types of devices have been proposed and used to indicate and determine the inclination of deep wells. Some devices that have been employed for this purpose are run into the drill pipe immediately before it is withdrawn from the bore while others require drilling operations to be suspended and the drilling string removed from the well to permit the surveying instrument to be lowered into the well.

It is a general object of this invention to provide a simple, practical, and effective surveying device for use in well drilling operations for indicating the inclination of a well bore.

It is another object of this invention to provide a well surveying device that is adapted to be arranged in an operating string carrying a drilling tool and which is operable to indicate to the driller or operator that the well bore is crooked or deviating from the vertical.

It is another object of this invention to provide a device of the character mentioned that is operable to record the extent of deviation or inclination of the well bore.

Another object of the invention is to provide a method for ascertaining whether the drilling tool is vertical or inclined. In accordance with the method provided by the present invention, the operator or driller may determine the position of the drilling tool, or, more properly, the vertical position of the operating string adjacent the drilling tool, by varying the pressure on the circulating fluid passing through the drilling string.

Another object of this invention is to provide a well surveying device of the character mentioned that may be reset in the unactuated position after actuation without being withdrawn from the well. The device is such that it may be operated to indicate to the driller that the well bore is being drilled crooked and may be reset after operation without being withdrawn from the well, so that means may be taken to straighten the well bore and drilling operations continued. In this manner a well may be drilled straight or vertical with great facility.

It is a further object of the invention to provide a well surveying device of the character mentioned that is simple in construction and

operation and which is constructed so that it will not be collapsed by the excessive hydrostatic or head pressures in the well bore.

Other objects and features of our invention will be best and more fully understood from the following detailed description of a typical form and application of the invention, throughout which reference is had to the accompanying drawing, in which:

Fig. 1 is a view illustrating the device provided by this invention mounted in a drilling string within a well bore. Fig. 2 is an enlarged longitudinal detailed sectional view of the device illustrating it in the normal or unactuated position. Fig. 3 is a view similar to Fig. 1 illustrating the device in the operated position. Fig. 4 is a transverse detailed sectional view taken as indicated by line 4—4 on Fig. 2.

The device provided by the present invention includes, generally, a body 10 adapted to be arranged in an operating string of drill pipe, or the like, a shell or cage 11 within the body 10, a valve 12 on the cage 11 operable to control the flow of fluid through the body 10, a plumb bob 13 within the cage 11 normally holding the valve 12 open and releasable to swing or oscillate to permit closing of the valve 12, means 14 for recording the extent of inclination of the well bore, and means 15 for equalizing the fluid pressures in the cage 11 and the operating string.

The body 10 is adapted to be arranged in an operating string of drill pipe, or the like, and is provided to carry or encase the various other parts of the device. The body 10 may be constructed for connection between various parts of an operating string. In the particular case illustrated in the drawing the body 10 is adapted to be connected between a sub 16 and a tool joint section 17. The body 10 is a tubular member having a central longitudinal opening 18 forming a fluid passage between the sub 16 and tool joint section 17. The body 10 is preferably arranged adjacent or immediately above the drilling tool or bit 19 carried at the lower end of the operating string. In the drawing the body 10 is shown connected with a drill collar 20 carrying the bit 19 by the tool joint section 17. The body 10 may be connected with the string of drill pipe by the sub 16 and a suitable tool joint 21. The upper portion of the opening 18 of the body 10 is screw threaded to receive the tapered screw-threaded pin 22 of the sub 16. A downwardly-projecting screw-threaded pin 23 may be provided at the lower end of the body 10 to thread into the box or socket of the tool joint section 17. An in-

ternal shoulder 24 is provided in the body 10 to carry the cage 11.

The shell or cage 11 is removably mounted or supported within the body 10. The cage 11 may include an upper or main section 25 for carrying the valve 12 and plumb bob 13 and a lower section 26 for carrying the means 14 and 15. The main section 25 of the cage 11 is tubular and has a radial enlargement or head 27 at its upper end for seating on the shoulder 24, a reduced neck portion 28 for carrying the stem of the valve 12, and an enlarged lower portion 29 encasing the plumb bob 13. The head 27 is provided with an upwardly-facing socket 30 for receiving or holding the head 15 of the valve 12. The head 27 may be provided with a beveled lower edge to cooperate with the beveled shoulder 24 of the body to support the cage within the body. The opening 31 of the lower portion 29 is comparatively large to provide space for the free swinging of the plumb bob 13. The lower section 26 may be screw threaded into the lower end of the portion 29, and the means 15 carried by the section 26 closes the lower end of the cage. The reduced portion 28 and the lower portion 29 and the section 26 are of less diameter than the opening 18 of the body 10 so that there is an annular passage through the body 10 for passing circulation fluid. A plurality of openings 32 are provided in the head 27 and 20 extend downwardly through the head from the bottom of the socket 30 to pass fluid into the body 10.

The valve 12 is provided to control the passage of fluid through the openings 32 and includes a stem 33 slidable in the reduced portion 28 of the case 11 and a head 34 in the socket 30 adapted to close the passages or openings 32. Rings 35 may be provided on the stem 33 to seal with the walls of the opening in the reduced part 40 28. The head 34 is provided with a flat lower side to cooperate with the bottom of the socket 30 to close the openings 32. The upper side of the head 34 may be convex or conical and is adapted to engage the lower end of the pin 22 to limit 45 upward movement of the valve. The valve 12 is normally held in the open position where the head 34 is spaced from the bottom of the socket 30 by the plumb bob 13 as will be hereinafter described.

The invention provides means for returning the valve 12 to the open position after it has been closed and for releasing the plumb bob 13 for movement upon the fluid pressure in the operating string being reduced. A helical spring 36 is arranged under compression between the lower 55 end of the stem 33 and an internal shoulder 37 in the cage 11. The valve 12 is adapted to be closed by pressure in the operating string acting downwardly on the head 34 when the plumb bob 13 is released and the spring 36 is operable to return the valve to the open position upon pressure on the fluid in the operating string being reduced.

The plumb bob 13 normally holds the valve 65 12 against downward movement and is releasably held in the normal unactuated position until the pressure on the fluid in the operating string is reduced when the spring 36 operates to release it so that it may swing from its normal central position to a true vertical position in the event that the well bore is crooked or inclined. The plumb bob 13 is suspended from the lower end of the stem 33 so that it is free to tilt or swing. A ball or sphere 40 is provided at the upper end of the plumb bob 13 and is seated in

a socket 41 in the lower end of the stem 33. A retaining member 42 may be screw threaded on a reduced part of the stem 33 to retain the ball 40 in the socket 41. A sharpened pin 43 is removably screw threaded on the lower end of the plumb bob 13 and normally extends into an opening 44 in the upper end of a rest 45 on the upper end of the section 26. The rest 45 is centrally located on the upper end of the section 26 and projects upwardly from the section 26. The pin 43 normally is held in the opening 44 of the rest to hold the plumb bob 13 against movement and to prevent closing of the valve 12 by the downward pressure of the fluid on the valve head 34. Upon the pressure on the fluid in the operating string being reduced, the spring 36 raises the valve 12 and plumb bob 13 so that the pin is freed from the opening 44 allowing the plumb bob to tilt or swing in the event that the well bore is inclined.

The means 14 for recording the inclination of the well bore includes a disk or plate 46 of a comparatively soft material mounted on the upper end of the lower section 26 and adapted to be engaged and marked or indented by the pin 43. The plate 46 may be formed of lead, or the like, and is mounted on the upper end of the section 26 around the rest 45. The upper side of the plate 46 may be concave to conform to the arc of oscillation of the plumb bob 13. The upper side of the plate 46 may be calibrated to indicate the extent of inclination of the well bore from the vertical. The pin 43 and plate 46 are related to the valve 12 so that the lower side of the valve head 34 is adapted to engage the bottom of the socket 30 to close the openings 32 when the pin engages the upper side of the plate 46.

The cage 11 is preferably filled with liquid to prevent the high head or hydrostatic pressures 115 in the operating string and well bore from collapsing the cage. The cage 11 may be filled with heavy oil, or the like. The invention provides means for equalizing the fluid pressures in the body 10 and the cage 11 so that the valve stem 120 33 is free to be operated in the opening of the cage. The lower section 26 of the cage has a downwardly-projecting tubular extension 50. Ports 51 communicate between the interior of the cage 11 and the upper end of the opening 52 125 of the extension 50. A piston 53 is slidably arranged in the opening 52. The piston 53 is normally yieldingly urged upwardly by a spring 54 arranged under compression between the lower end of the piston 53 and a nut or plug 55 threaded 130 into the lower end of the extension 50. The plug 55 is provided with an opening 56 communicating with the opening 52 to permit the fluid pressure in the body and operating string to act against the lower side of the piston 54. During the course 135 of normal drilling operations the fluid pressure in the operating string acts against the piston 53 so that the pressure on the fluid in the case 11 is equal to the pressure on the fluid in the operating string.

In carrying out the method provided by the invention, the surveying device is arranged in the operating string carrying a drilling bit 19, or the like, and is preferably arranged in the string a short distance above the bit. The valve 12 is normally in the open or intermediate position illustrated in Fig. 2 and is retained in this position by the circulation fluid passing downwardly through the operating string and acting against the upper end of the head 34. When it is desired 150

to determine whether the well bore is inclined, the pressure on the circulation fluid is reduced so that the spring 36 moves the valve 12 and the plumb bob 13 upwardly. Upon upward movement of the plumb bob it is freed from the support 45 and permitted to swing to a vertical position.

In the event that the well bore and the operating string are inclined from the vertical, as illustrated in Fig. 3 of the drawing, the plumb bob will swing to a position out of alignment with the rest or support 45. Pressure is then applied to the fluid in the operating string which forces the valve 12 and plumb bob 13 downwardly, causing the pin 43 to engage the plate 46 and closes the valve 12. Upon the valve 12 being closed, the pumps supplying the circulation fluid to the operating string will labor and inform the driller or operator that the flow of circulation fluid is stopped. Engagement of the pin 43 with the plate 46 makes an impression on the plate to indicate the inclination of the well bore. The device may be withdrawn from the well, if desired, for inspection to determine the extent of inclination, or the operating string may be raised a short distance to bring the device into a straight vertical portion of the bore, and, upon pressure being taken off the fluid in the operating string, the spring 36 moves the valve 12 and plumb bob 13 upwardly so that the pin 43 will be in alignment with the opening 44. Pressure may then be applied to the fluid in the operating string to move the valve 12 and plumb bob 13 downwardly to bring a pin 46 into the opening 44. With the parts in this position, fluid is free to flow through the operating string and drilling operations may be continued or means taken to straighten the well bore. In practice, the pressure on the circulation fluid may be reduced at any given interval (either of time or of distance drilled) and upon the driller becoming aware that the drilling tool is not forming a vertical hole, means, well known to well drillers, may be taken to connect the deviation of the hole before continuing the usual drilling operations. In most cases the deviation may be corrected without removing the drill pipe from the well bore. It will be obvious that with the use of the device of this invention, a true vertical well bore may be drilled with great ease.

It is to be noted that the invention provides a well surveying instrument that may be connected in an operating string carrying a drilling tool and which may be operated at given intervals or as desired to determine whether the well bore is straight. The device may be reset in the normal position after actuation in the manner described above without being withdrawn from the well bore. With the device in its normal position it does not interfere with the circulation of fluid through the operating string. The pin 43 is removable so that pins of various sizes may be mounted at the lower end of the plumb bob. If desired or practical, removable and interchangeable rests 45 having sockets 44 of various sizes may be provided on the cylinder. By varying the size of the pin at the lower end of the plumb bob, or the rest 45, or both, the plumb bob may be freed from the rest 45 upon the device being operated in a well bore having any given inclination. The cage 11 may be easily removed from within the body 10 and the section 26 disconnected from the section 25 so that the plate 46 may be inspected to determine the extent of inclination recorded on the plate.

Having described only a typical preferred form

of our invention, we do not wish to limit ourselves to the specific details set forth, but wish to reserve to ourselves any changes or variations that may appear to those skilled in the art or fall within the scope of the following claims:

Having described our invention, we claim:

1. A device of the character described including, a body adapted to be mounted in an operating string of drill pipe, the body having an opening communicating with the drill pipe, a valve operable to control the passage of fluid through the opening, a plumb bob connected with the valve, means for releasably holding the plumb bob against movement in a position where it holds the valve open, and means for releasing the plumb bob for movement upon the fluid pressure in the operating string being reduced. 80

2. A device of the character described including, a tubular body adapted to be mounted in a string of drill pipe, a valve operable by fluid pressure in the drill pipe to prevent the flow of fluid through the body, a plumb bob connected with the valve, means releasably holding the plumb in a position where it prevents closing of the valve, and means for releasing the plumb bob upon the pressure on 100 the fluid in the drill pipe being reduced. 95

3. A device of the character described including, a tubular body adapted to be mounted in a string of drill pipe, a valve operable by fluid pressure in the drill pipe to restrict the flow of fluid 105 through the body in one direction, a plumb bob connected with the valve, means releasably holding the plumb bob in a position where it prevents operation of the valve, and means for releasing the plumb bob for oscillation upon the pressure 110 on the fluid in the drill pipe being reduced, the valve being operable upon release of the plumb bob to restrict the flow of fluid through the body in one direction.

4. A device of the character described includ- 115 ing, a tubular body adapted to be mounted in a string of drill pipe, a valve operable by fluid pressure in the drill pipe to prevent the flow of fluid through the body, a plumb bob connected with the valve, means whereby fluid pressure holds 120 the plumb bob against movement in a position where it prevents closing of the valve, and means for releasing the plumb for movement upon pressure in the drill pipe being reduced.

5. A device of the character described includ- 125 ing, a tubular body adapted to be mounted in a string of drill pipe, a valve operable by fluid pressure in the drill pipe to restrict the flow of fluid through the body, a plumb bob connected with the valve, a rest supporting the plumb bob in a 130 vertical position against movement where it prevents operation of the valve when the fluid in the drill pipe is under a predetermined pressure, and means for releasing the plumb from the rest upon the pressure in the drilling string being reduced to permit operation of the valve by fluid pressure in the event the plumb bob is out of vertical alignment with the rest.

6. A device of the character described includ- ing, a tubular body adapted to be mounted in a string of drill pipe, a valve operable by fluid pressure in the drill pipe to restrict the flow of fluid through the body, a plumb bob connected with the valve, a rest supporting the plumb bob in a vertical position against movement where it holds the valve against operation when the fluid in the drill pipe is under a predetermined pressure, means for releasing the plumb bob from the rest to release the valve for operation upon the pressure in the drill pipe being reduced, and means for

recording the position of the plumb bob in the event it swings out of engagement with the rest.

7. A device of the character described including, a tubular body adapted to be mounted in a string of drill pipe, a valve operable by fluid pressure in the drill pipe to prevent the flow of fluid through the body, a plumb bob connected with the valve, a rest supporting the plumb bob in a vertical position against movement where it prevents closing of the valve when the fluid pressure in the drill pipe is at a predetermined pressure, means for releasing the plumb bob from the rest to release the valve for operation upon the pressure in the drill pipe being reduced, and means for recording the position of the plumb bob when the pressure in the drill pipe operates the valve in the event that the plumb swings out of alignment with the rest.

8. A device of the character described including, a tubular body adapted to be mounted in a string of drill pipe, a valve operable by fluid pressure in the drill pipe to restrict the flow of fluid through the body, a plumb bob connected with the valve, a rest supporting the plumb bob in a vertical position against movement where it holds the valve against operation when the fluid pressure in the drill pipe is at a predetermined pressure, means for releasing the plumb bob from the rest to release the valve for operation upon the pressure in the drill pipe being reduced, and means for recording the position of the plumb bob when the pressure in the drill pipe operates the valve in the event that the plumb swings out of alignment with the rest, said recording means including an impressionable plate adapted to be engaged by the plumb bob.

9. A device of the character described including, a tubular body adapted to be mounted in a tubular operating string, a cage mounted in the body and spaced from the walls of the body, a valve operable by pressure in the string to restrict the passage of fluid through the body, a stem on the valve slidable in the cage, a plumb bob attached to the stem and disposed within the cage, a rest engaging the plumb bob to hold it against movement in a position where it holds the valve against operation, and means for releasing the plumb from the rest to permit swinging of the plumb out of alignment with the rest so that the valve may operate.

10. A device of the character described including, a tubular body adapted to be mounted in a tubular operating string, a cage mounted in the body and spaced from the walls of the body, a valve operable by pressure in the string to restrict the passage of fluid through the body, a stem on the valve slidable in the cage, a plumb bob attached to the stem and disposed within the cage, a rest engaging the plumb bob to hold it against movement in a position where it holds the valve against operation, means for equalizing the fluid pressures in the cage and body, and means for releasing the plumb from the rest to permit swinging of the plumb out of alignment with the rest so that the valve may operate.

11. A device of the character described including, a tubular body adapted to be mounted in a tubular operating string, a cage mounted in the body and spaced from the walls of the body, a valve operable by pressure in the string to restrict the passage of fluid through the body, a stem on the valve slidable in the cage, a plumb bob attached to the stem and disposed within the cage, a rest engaging the plumb bob to hold

it against movement in a position where it holds the valve against operation, means for equalizing the fluid pressures in the cage and body including a piston slidably carried by the cage and having one end acted upon by fluid pressures in the interior of the body and an opposite end for acting on the fluid in the cage, and means for releasing the plumb from the rest to permit swinging of the plumb out of alignment with the rest so that the valve may operate.

80

85

90

95

12. A device of the character described including, a tubular body adapted to be mounted in a tubular operating string, a cage mounted in the body and spaced from the walls of the body, a valve operable by pressure in the string to restrict the passage of fluid through the body, a stem on the valve slidable in the cage, a plumb bob attached to the stem and disposed within the cage, a rest engaging the plumb bob to hold it against movement in a position where it holds the valve against operation, and means for releasing the plumb bob from the rest to permit swinging of the plumb out of alignment with the rest so that the valve may operate, including a spring engaging the stem and adapted to raise the valve and plumb bob upon the pressure in the operating string being reduced.

13. In a well surveying device, a tubular body adapted to be mounted in a tubular operating string, an impression plate in the body, a plumb bob in the body operable to mark the impression plate, means normally releasably holding the plumb bob against movement, and means operable by reducing the pressure on fluid passing through the operating string to release the plumb bob and to operate it into engagement with the impression plate, the last mentioned means including a valve connected with the plumb bob and acted on by the fluid in the operating string.

115

14. In a well surveying device, a tubular body adapted to be mounted in a tubular operating string, an impression plate in the body, a plumb bob in the body operable to mark the impression plate, means normally releasably holding the plumb bob against movement, and means operable by reducing the pressure on fluid passing through the operating string to release the plumb bob for movement and operation, the last mentioned means including a spring pressed valve operatively connected with the plumb bob and acted upon by the fluid in the operating string.

120

15. In a well surveying device, a tubular body adapted to be mounted in a tubular operating string, an impression plate in the body, a plumb bob in the body operable to mark the impression plate, and fluid pressure actuated means for normally holding the plumb bob against operation and operable to release the plumb bob for movement upon the pressure on the fluid passing through the string being reduced.

130

16. In combination, an operating string of drill pipe for passing fluid under pressure into a well bore from a fluid pressure system, and a device mounted in the string including a tubular body interposed in the string of pipe, and means in the body operable to modify the action of the fluid pressure system to indicate to the operator that the device has deviated from the vertical, said means including a valve in the body operable to restrict the flow of fluid through the body, an element movable by gravity connected with the valve and normally held against movement in a position where it holds the valve against operation, and means for releasing the valve and

145

150

said element for operation upon the pressure on fluid in the string being reduced.

17. In a well surveying device adapted to be arranged in a string of drill pipe, a body adapted to be arranged in the string, an impression disc in the body, a gravity governed member adapted to make an impression in the disc, fluid pressure controlled means normally holding the member against movement, and means for releasing the member for movement upon a reduction in the pressure on the fluid in the string, the fluid pressure controlled means being operable to move the member into engagement with the disc after operation of the last mentioned means.

15

18. In a well surveying device adapted to be arranged in a string of drill pipe, a body adapted to be arranged in the string, an impression disc in the body, a gravity governed member adapted to make an impression in the disc, a part engageable by the member to hold the member against movement, means for releasing the member from said part, and fluid pressure actuated means for operating the member into engagement with the disc and for restricting the flow through the string in the event that the body is not vertical.
